UNITED STATES PATENT OFFICE.

JACOB HÄUSLE, OF FELDKIRCH, AUSTRIA.

FOLDING LADDER.

Application filed December 15, 1925, Serial No. 75,585, and in Austria August 18, 1924.

This invention relates to improvements in flexible ladders and has for its object to reduce the weight and increase the strength and stability of the ladder.

5 Folding, flexible ladders of this kind generally comprise two ropes of wire or hemp or the like immovably secured to suitably spaced discs, rungs of steel or the like being fixed to the latter when the ladder is fitted 10 up for use and the said discs holding the ropes and rungs some distance away from the wall or the like. The discs are immovably secured to the ropes by passing the latter through grooves or guides provided in 15 the discs in the transverse direction thereof.

According to the invention the rope is wound once or several times round the sleeve of the disc fixed to a tubular member, so that the said rope is immovably retained 20 on the tubular member by means of the disc.

However the rope is wound round the sleeve of the disc in such a manner, that the direction in which the pull is exerted passes 25 exactly through the axis of the rope, so that neither the disc nor the rope is subjected to a lateral force, whereby the security of the ladder is considerably increased.

In order to prevent the rope from slipping in the guides or grooves, the discs are made 30 of a rigid, but pliable, material, such as aluminum or the like, so that during the depression of the guide-straps onto the rope the material is pressed into the depressions of the rope. The discs are stiffened by ribs 35 or grooves extending vertically with respect to the direction of the rope.

Of course the discs may be of any desired polygonal shape and material.

A preferred embodiment of carrying out

the present invention is illustrated by way 40 of example on the accompanying sheet of drawings in which—

Figs. 1 and 2 show in sectional side view and front view respectively one embodiment of the present invention taken on the lines 45 1—1 and 2—2 of Figures 2 and 1, respectively.

In the embodiment shown in Figs. 1 and 2, the reference character 1 designates a rope made of wire, hemp or the like, 2 designates a disc provided with guides or eyes 3, and 4 represents a steel tube enclosed in a sleeve 5 of wood or the like and forming the rung. The rope is drawn through eyes 3 formed by cutting and stamping the parts 55 out of the metal disc 2 and the rope is wound round the boss 6 of the disc 2 in such a manner, that two or more loops 7 are formed, and now the rope is again passed through the eyes. It is obvious, that the middle 60 plane of the loops exactly passes through the axis of the rope.

The boss of the disc 2 terminates in a flared end 8, in order to prevent any lateral movement of the loops, and the tube 4 is furnished with a flared end 9, in order to increase the strength and stability of the entire combination.

I claim—

In a flexible ladder, a disc, said disc being 70 provided with a centrally disposed tubular boss and a plurality of eyes disposed on a diametrical line of said disc, and a flexible member wound around said tubular boss and passing through said eyes. 75

In testimony whereof I affix my signature.

JACOB HÄUSLE.
